(57) CLAIM

The ornamental design for a vehicle operator document holder, as shown and described.

DESCRIPTION

FIG. 1 is a side perspective view of a vehicle operator document holder showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view, the right side elevation view being a mirror image thereof;

FIG. 7 is detail sectional view taken along line 7-7 of FIG. 2;

FIG. 8 is a detail sectional view taken along line 8-8 of FIG. 2;

FIG. 9 is a detail sectional view taken along line 9-9 of FIG. 2; and,

FIG. 10 is a side elevation view thereof, shown in use applied to a visor of a motor vehicle.

The broken lines shown in the drawings illustrate portions of the vehicle operator document holder that form no part of the claimed design.

The broken lines in FIG. 10 showing the vehicle operator document holder in use illustrates environment and forms no part of the claim.

1 Claim, 6 Drawing Sheets
